HEEL-SEAT FITTING MACHINE

William D. Thomas, Lynnfield, Mass., assignor to
United Shoe Machinery Corporation, Paterson,
N. J., a corporation of New Jersey

Application August 26, 1938, Serial No. 226,995

9 Claims. (Cl. 12—31.5)

This invention relates to the manufacture of shoes and is illustrated as embodied in a machine for fitting the heel-seat portions of attached soles of shoes for the reception of heels having sole-receiving channels of the type disclosed in United States Letters Patent No. 2,121,172, granted June 21, 1938, on an application filed in the name of Fred C. Lovejoy.

It is an object of the invention to provide a machine for quickly and effectively reducing the heel-end portions of previously attached short soles intended to be interlocked with heels having sole-receiving channels, such heels being hereinafter referred to as interlocking heels, and particularly to equip the commercial heel-seat fitting machine which is disclosed in United States Letters Patent No. 2,053,295, granted September 6, 1936, on an application filed in the name of Fred L. MacKenzie, and which is adapted to reduce the heel-seat portions of attached full-length soles of shoes for the reception of ordinary Louis and Cuban heels, with suitable interchangeable parts for accommodating short sole and channeled heel work.

With the above object in view, and in accordance with a feature of this invention, there are provided, in combination with means for reducing the heel-end portion of an attached sole of a shoe for the reception of an interlocking heel, a back gage for positioning the heel-seat portion of the shoe with relation to said means, a gage comprising relatively movable abutments constructed and arranged to engage the rear end of the heel and the bottom of a sole-receiving channel formed in the breast of the heel, respectively, and mechanism movable in response to the relative movement of said abutments for so locating the shoe back gage relatively to the reducing means that the fitted sole will be of the correct length to properly fit the channel in that particular heel.

Various other features of the invention, including the provisions for adapting the machine to operate on ordinary work or short sole work, will be understood from the following detailed description read in connection with the accompanying drawings, in which—

Fig. 1 is a perspective view, partly in section and partly broken away, of the illustrated machine equipped to trim the heel end of the attached sole of a shoe to the form illustrated in Fig. 4 for the reception of an interlocking heel;

Fig. 2 shows in perspective the heel gage and the sole-trimming mechanism of the machine equipped to trim the heel end of the attached

sole of the shoe to the form illustrated in Fig. 5 for the reception of the interlocking heel;

Fig. 3 is an exploded view showing the commercial heel gage used in operating upon Louis and Cuban work, and the under side of a platform which may be positioned upon said heel gage to equip the machine for operating upon interlocking work;

Figs. 4 and 5 are perspective views showing the heel ends of shoes the attached soles of which have been trimmed by the machine equipped as illustrated in Figs. 1 and 2, respectively; and

Fig. 6 shows a covered interlocking heel.

The illustrated machine will be described with reference to reducing the heel ends 20 (Fig. 4) 15 22 (Figs. 2 and 5) of attached short outsoles 24, 26, respectively, of shoes 25 for the reception of interlocking heels 28. The interlocking heel 28 has at the upper end of its breast a forwardly projecting lip 30 which is of less width than the upper end of the breast of the heel, and a channel 32 (Fig. 6) the upper wall 34 of which is formed by the lower face of the lip, and the lower wall 36 of which extends from one side of the attaching face 38 of the heel to the other. In the finished shoe to which the heel 28 is attached the forwardly projecting lip 30 is positioned between the outsole 24 (Fig. 4) or 26 (Fig. 5) of the shoe 25 and the bottom of the shoe, the rear end of the reduced outsole of the shoe fitting in the channel 32 of the heel. This interlocking construction and the advantages thereof are fully disclosed in the above-mentioned United States Letters Patent No. 2,121,172.

In order that the rear end of the reduced outsole shall fit in the channel 32 of the heel 28 positioned upon the shoe 25 it has been proposed to trim the heel end 20 of the sole 24 from one side to the other by a straight cut, as illustrated in Fig. 4, forming a rear face 40 which is spaced 40 a distance 41 from the heel-breast line 42 of the sole, the distance 41 being slightly less than the depth of the channel 32 formed in the heel. The heel end reducing operation just described has been found to be quite satisfactory when the lateral margins of the sole have been previously beveled to a feather edge, as shown in Fig. 4, since the lateral margins of the channel-entering portion 44 of the sole can then be quickly and effectively inserted, without crowding, into the end portions of the channel 32.

When the lateral margins of the heel end of the sole have not been previously reduced to a considerable extent, as illustrated in Fig. 5, I have found it preferable to form a tab or chan-

nel entering portion 46 of the sole, the tab having a rear face 48 and beveled lateral margins 50 extending forwardly to or approximately to the ends of the heel-breast line 52 of the sole 26. The tab 46 may be described as tapering rearwardly from the ends of the heel-breast line of the sole.

The face 48 (Fig. 4) at the rear end of the trimmed sole 24 is formed by a knife 54 (Fig. 1) which has a straight cutting edge 56 and is movable in a vertical path past the straight front edge 58 of a sole-supporting plate 60 upon which the heel end 20 of the attached sole 24 of the shoe is supported. The tab 46 (Fig. 5) is formed by a knife 62 (Fig. 2) comprising straight cutting edges 64, 66 which are offset lengthwise and widthwise from each other and are joined by beveling cutting edges 68, the knife being movable in a vertical path past the front edge 70 of a sole-supporting plate 72, which has a shape 20 corresponding to that of the continuous cutting edges 64, 68 and 66 of the knife 62.

Three interchangeable sets of cooperating knives 62 and plate 72, such as illustrated in Fig. 2, are provided to accommodate a run of shoes. It will be appreciated that since each set of cooperating knives 62 and plates 72 has to accommodate several different widths of soles, the beveled margins 50 of the tabs 46 formed by the cutting edges 68 only extend to the sides of the sole 30 in the case of the smallest sole to be operated upon by that particular set of knives and plates. When a sole larger than said smallest sole is operated upon by said set of knives and plates, narrow shoulders 74 (Fig. 5) against which the 35 upper breast corners of the heel abut, are formed on the sole, the width of the shoulder varying in accordance with the width of the sole. The narrow shoulders of the finished shoe are not supported against drooping away from the shoe upper by the heel, and it is therefore desirable that the next larger set of knives 62 and plates 72 be used when the width of the shoulders becomes substantial.

The sole-reducing knife 54 or 62 is clamped by 45 a screw 76 (Fig. 2) to a vertically reciprocating slide 78 of the commercial machine which is disclosed in said United States Letters Patent No. 2,053,295 and which is adapted to fit the heel-seat portions of attached soles of shoes for the 50 reception of ordinary Cuban and Louis heels.

The plate 60 or 72 is located and held in its operative position in guideways 80 (Fig. 2) of the machine frame 81, in place of the crease plate (not shown) of the commercial machine, 55 through the provision of a rod 82 which may be moved to the left as viewed in Fig. 2, by the operator, against the action of a spring (not shown) to withdraw a tapered end (not shown) of the rod from a correspondingly shaped recess (not 60 shown) in the side of the plate, preparatory to removing the plate from the machine. In positioning the selected sole-supporting plate 60 or 72 in the machine the operator moves the rod to the left as above described and slides the plate 65 rearwardly to its approximate operating position in the guideways 80. The rod 82 is then released and the plate 60 or 72 is moved slightly lengthwise until the tapered end of the rod is forced by the spring into the tapered opening in the 70 side of the plate.

In order to position the heel end 20 (Fig. 4) 22 (Fig. 5) of the attached sole 24, 26, respectively, upon the selected plate 60 (Fig. 1) or 72 (Fig. 2), the machine is provided with a centralizing slide 84 (Figs. 1 and 2) and a back gage

86 constructed and arranged to be engaged by the counter portion of the shoe upper. The construction and operation of the centralizing slide 84 and the back gage 86 which is substantially identical with corresponding mechanism of the 5 machine disclosed in said Letters Patent No. 2,053,295, will be described later. It will be noted that when the machine is operating upon interlocking work the heel gage 86 (Fig. 1) comprises an extension block 83 (Fig. 1) which is detachably secured to the front end of the heel gage of the commercial machine. The extension block 83 has secured to it a pin 85 which fits in a recess formed in the front end of the heel gage of the commercial machine and is held in said recess by a spring-pressed plunger 87.

The commercial machine may be readily converted into a machine for trimming attached soles of shoes for the reception of interlocking heels 28. Such a change is quickly effected by 10 substituting the knife 54 and the plate 60 when it is desired to trim the sole to the form illustrated in Fig. 4, or by substituting the knife 62 and the plate 72 when it is desired to trim the sole to the form illustrated in Fig. 5, in place 15 of the crease plate (not shown) and the shoulder-forming knives (not shown) of the commercial machine, and by providing a modified gage, which will effectively measure the interlocking heel, in place of the heel gage of the commercial 20 machine. Moreover, since the heel end of the sole is reduced by the vertically moving knives 54, 62, the horizontally moving cutter (not shown) of the commercial machine, which reduces the heel-seat portion of the sole by a beveling cut, is removed from the machine.

It will be noted that the plates 60 (Fig. 1) 72 (Fig. 2) are provided with beveled faces 88, 90, respectively, against which the rear ends of out-soles of full length are forced by a U-shaped 40 clamp 92 (Fig. 1) of the commercial machine. In operating upon short soles the clamp 92 is removed from the machine since the heel end of the sole is then effectively forced against the forward part of the plate 60 or 72 by clamps 93 45 which are practically identical with corresponding clamps of the commercial machine. The clamps 92 and 93 are yieldingly mounted upon a vertically movable plunger 94 operated by a treadie (not shown). In operating upon interlocking 50 work a bulger (not shown) which is mounted upon the lower end of the plunger 94 of the commercial machine and which forces the central part of the heel-seat portion of the sole through the U-shaped opening of the crease plate when 55 operating upon attached soles of shoes which are to receive Cuban or Louis heels, is removed from the plunger.

The heel gage of the commercial machine comprises a table 96 (Fig. 3) upon which the Louis 60 or the Cuban heel to be applied to the shoe being operated upon is positioned attaching-face down. In order to measure a Louis heel 97 (Fig. 3) the heel gage is provided with an abutment 98 (Figs. 1 and 3) movable forward and rearward over the 65 table 96, and a bar 100 (Fig. 3) which may be swung about a fixed pivot 102 into its operative position shown in full lines or into its vertical inoperative position shown in dotted lines. The abutment 98 is secured through a screw-and-slot 70 connection 104 to a slide 106 (Figs. 1 and 3) which is movable forward and rearward in a T-shaped guideway 108 of the table 96 and is pivoted at its rear end to the upper arm 110 (Fig. 1) of a yoke 112 pivoted on a bearing pin 114 se- 75

cured to the main frame 81 by a screw 116. The yoke 112 is normally urged in a clockwise direction as viewed in Fig. 1 by a coil spring 118 the lower end of which is secured to a stud 120 carried by the pin 114 and the upper end of which is secured to a stud 122 carried by the yoke 112. The lower arm 124 of the yoke 112 is provided with a gear segment 126 meshing with a gear 128 supported by and pivoted upon a bearing pin 130 which is secured by a screw 132 to the main frame 81 and has a flange at its lower end. Mounted for rotation upon the bearing pin 130 and secured to the gear 128 by a binding pin 134 is a stop 136 which has a spiral outer face 138 and has secured to it a stud 140. When the heel is removed from the heel gage, rotation of the stop 136 in a counterclockwise direction, as viewed in Fig. 1, and therefore forward movement of the abutment 98 under the action of the spring 118, is limited by the engagement of the stud 140 with a post 142 secured to the main frame 81.

When it is desired to measure a Cuban heel (not shown) in the heel gage, the bar 100 is moved into its inoperative position shown by dotted lines in Fig. 3, and an abutment 144 is swung 180° from its inoperative position illustrated in Fig. 3 about a pivot screw 146 which passes through a recess in the abutment 144 and is threaded into a slide 147 (Fig. 2). The slide 147 may be moved forward and rearward to its operative position in the table 96 by turning a screw 149 (Fig. 2) which is threaded into the table and has a flange 151 fitting in a slot 153 in the side of the slide. The abutment 144 is held in its operative and inoperative positions upon the table 96 by a spring-pressed detent 155 (Fig. 3) which fits in a recess of the table 147 and registers with an elongated groove 157 formed at the under side of the abutment 144. In measuring the Cuban heel the concave breast of the heel is forced through mechanism above described against a convex face 148 of the abutment 144 by the movable abutment 98.

Rearward movement of the centralizing slide 84 and the back gage 86 is limited by the stop 136 through mechanism which will now be described, the stop being rotated to a predetermined operative position through the above-described mechanism in accordance with the size of a heel positioned in the heel gage. The abutment 98 (Figs. 1 and 3) is engaged by the rear end of the rim of the attaching face of the Louis heel 97 (Fig. 3) and is moved rearwardly by the heel grasped in the left hand of the operator, until the heel can be placed attaching-face down upon the table 96 between the abutment 98 and the bar 100. When the heel is released by the operator the sliding abutment 98 is moved forwardly through the mechanism above described, the arrangement being such that the breast of the heel is forced against the bar by the sliding abutment 98 and is properly oriented upon the table. The heel thus clamped between the abutment 98 and the bar 100 has its attaching face measured lengthwise. When the heel gage is operating on Cuban work, the Cuban heel is measured in a similar manner, the breast of the heel being forced against the convex face 148 of the abutment 144 which is swung around 180° from the position shown in Fig. 3, as above described.

The back gage is moved forward and rearward along a straight groove 158 (Fig. 1) in the lower face of a stop plate 152 which is slidable along a pair of opposed rectilinear guideways 154 of the

machine frame 81. The centralizing slide 84 which has work-engaging faces 156 (Figs. 1 and 2) is also mounted for movement along a pair of opposed guideways 158 which are parallel to and are positioned above the respective guideways 154. The centralizing slide 84 is normally urged forward against an upstanding lug 160 of the stop plate 152 by a pair of springs 162 (only one of which is shown) which are enclosed in recesses 164 of the centralizing slide 84 and engage the forward ends of rods 166 which fit in the respective recesses and engage a lug 168 secured to the main frame 81. When the machine is idle the back gage 86 is normally held in its advanced inoperative position shown in Fig. 1 in front of the stop plate 152 by a spring 170, forward movement of the back gage with relation to the stop plate being limited by the engagement of a shoulder 172 of the back gage with the rear end of the stop plate. Extending through an elongated slot 174 of the back gage is a block 176 supported by a screw 178 which is threaded into the stop plate 152 and has an enlarged portion 180 located in a recess 182 of the block. A depending pin 184 is secured to the stop plate 152 and fits in a cylindrical recess 186 of the block 176, the arrangement being such that the block may be swung laterally with relation to the stop plate about the pin 184 within limits determined by the enlarged portion 180 of the screw 178.

As above described, the stop plate 152 is normally urged forward by the centralizing slide 84 which, in turn, is constantly urged forward by springs 162. In order to limit forward movement of the stop plate 152 the block 176, which is carried by the stop plate, has secured to it a depending rod 188, which when the block is moved forward to a predetermined position, engages the main frame 81. The block 176 has a concave cylindrical face 190 which when the block is moved rearward engages the spiral face 138 of the previously adjusted stop 136 thereby limiting rearward movement of the stop plate and the back gage 86. The counter portion of the shoe is forced against the respective work-engaging faces 156 of the centralizing slide, and as the shoe is forced rearward its rear end engages the back gage 86 forcing the same, together with the centralizing slide 84, rearward. As the back gage 86 is moved rearward by the shoe it engages the stop plate 152 and moves the same rearward until the face 190 of the block 176 carried by the stop plate 152 engages the stop 136. It will be clear that the position of the shoe in the machine depends upon the angular setting of the stop 136 which is connected through the above-described mechanism to the movable abutment 98 of the heel gage.

As above explained the heel gage of the commercial machine may be quickly modified so as to accommodate interlocking heels. Preparatory to trimming the rear end of the sole straight across, as illustrated in Fig. 4, for the reception of the interlocking heel, a platform or unit 192 (Figs. 1 and 3) is mounted upon the table 96. The platform 192 is provided at its under side with a slot 194 (Fig. 3) for receiving the bar 100 and has secured to it a depending pin 196 constructed and arranged to fit in a recess 198 of the table 96. The platform 192 comprises a base portion 200 and a sole-supporting plate 202 having a depending flange 204 which fits in a forwardly and rearwardly extending groove 206 of the base portion 200. The heel-supporting plate 202 also has a laterally extending shoulder 210.

against which the rear end of the interlocking heel is forced, as illustrated in Fig. 1, by a finger 212 carried by the abutment 98. In order to vary the operative position of the shoulder 210 the plate 202 may be secured in different adjusted positions upon the base portion 200 through the provision of a screw 211 which is threaded into the base portion and passes through a slot 213 formed in the plate. The finger 212 is curved transversely in accordance with the curvature of the channel 32 of the heel and may be swung to its inoperative position shown in Fig. 3 when the gage is equipped to accommodate Louis or Cuban heels or to its operative position shown in Fig. 1 to engage the bottom of the sole-receiving channel 32 of the interlocking heel 28 mounted upon the platform 192 and to force the heel against the shoulder 210 of the platform.

When the heel-end of the attached sole of the shoe is reduced by the machine equipped with the knife 62 (Fig. 2) and the plate 72 to provide the tab 46 (Fig. 5) it is customary to support the heel upon a slightly different type of platform or unit 214 (Fig. 2) which is similar to the platform 192, but has a pair of abutments 216 which are engaged by the breast of the interlocking heel. The platform 214 comprises a base portion 218 which is identical with the base portion 200 of the platform 192, and a heel-supporting plate 30 220 having grooves 222 along which the respective abutments 216 may be set in different adjusted positions through the provision of the screw-and-slot connections 224. When the interlocking heel has been placed upon the table 35 220 by the operator, an abutment 226 corresponding to the abutment 98 forces the upper breast corners of the heel against the respective abutments 216 in the same manner that the abutment 98 forces the breast of the Louis heel against the bar 100 (Fig. 3). In order to vary the lengthwise operative positions of the abutments 216 the plate 220 may be secured in different adjusted positions upon the base portion 218 through the provision of a screw 225 which is threaded into the base portion and passes through a slot 227 formed in the plate.

It is desirable that the abutments 216 engage only the upper breast corners of the heel, and with such an arrangement it has been found that there is a tendency for the forward end of the heel when forced against the abutments 216 to rise out of the gage. Accordingly the plate 220 has secured to it a leaf spring 228 (Fig. 2) which is flexed upwardly by the lip of the heel positioned upon the platform, the spring holding the heel against the above-mentioned tendency to ride up over the abutments 216 and therefore to be forced out of its operative position in the heel gage. Interlocking heels may be effectively measured by the above-described mechanism illustrated in Fig. 2 when the sole-receiving channels of the heels are of substantially uniform depth.

The heel end of the sole of the finished shoe should extend to or almost to the bottom of the channel 32 of the attached interlocking heel 28 of the shoe 25. It is therefore desirable that when the interlocking heel is positioned in the heel-measuring gage, as illustrated in Figs. 1 and 2, the stop 136 should be so positioned as to be engaged by the block 176 forced rearwardly by the shoe, when a transverse section of the attached sole of the shoe corresponding to faces 40 (Fig. 4) 48 (Fig. 5) is arranged in the path of movement of the cutting edge 56 (Fig. 1) of the

cutter 54 or the cutting edge 64 (Fig. 2) of the cutter 62.

In order to position the abutment 98 (Fig. 3) in correlated position with the stop 136 to adapt the machine for operating upon Louis work, the movable abutment 98 is initially adjusted as above described with reference to the slide 106. It is undesirable to disturb this adjustment between the abutment 98 and the slide 106 when changing over to other types of work and, accordingly, the above-described separate gaging mechanism is provided to adapt the machine for interlock work.

It will be appreciated that the distance between the face 40 (Fig. 1) or the face 48 (Fig. 5) formed upon the attached soles 24, 26, respectively, of shoes, and the rear ends of said shoes, is considerably less than the distances between heel-breast receiving shoulders formed upon attached soles of corresponding shoes which are to receive Louis or Cuban heels, and the rear ends of said corresponding shoes. Accordingly, in order that the same portion of the face 138 of the stop 136 used in connection with Cuban and Louis work may also be used in connection with interlocking work, the extension block 83, which is secured to the front end of the back gage 86 equipped for Louis or Cuban work, has a thickness 230 equal approximately to the average depth of the channel of the breastlock heel. As above 30 stated, the extension block 83 may be quickly secured to the back gage 86 of the machine equipped for operating upon Louis or Cuban work by inserting a pin 85 carried by the block 83 in a recess of the back gage, the block being held in 35 place by a spring-pressed plunger 87.

In order initially to adjust the machine so as to form a face 40 (Fig. 4) at the proper location lengthwise of the attached sole of the shoe, the operator, after positioning the interlocking heel 40 upon the shoe, draws a heel-breast line across the sole of the shoe. A second line, which is parallel to said heel-breast line and is set back on the sole a distance equal to the depth of the channel 32 of the heel 28, is then drawn across the 45 sole. The operator then forces the shoe against the centralizing slide 84 and the back gage 86 until said second line on the sole is in alignment with the front edge 58 of the plate 60. In positioning the shoe as above described the block 176 50 is moved rearward to a predetermined position through the above-described mechanism. The screw 211 which secures the plate 202 to the base portion 200 of the platform 192 is then released and the heel is positioned upon the plate 202 with 55 its rear end in engagement with the shoulder 210, the gaging finger of the abutment 98 engaging the bottom of the sole-receiving channel 32 of the heel, as illustrated in Fig. 1. While retaining the shoe in the above-mentioned position the operator slides the plate 202 of the platform 192 rearward with reference to the base portion 200 of the platform until the face 138 of the stop 136 60 has been swung into forced relation with the face 190 of the block 176. The screw 211 is then 65 tightened to secure the plate 202 in its proper adjusted position upon the base 200.

In order initially to adjust the machine equipped with the attachment illustrated in Fig. 2 for operating upon interlocking work, the operator, after positioning the interlocking heel 28 upon the shoe, draws a heel-breast line across the sole of the shoe. The shoe is then forced against the centralizing gage 84 and the back gage 86 until the said line is in alignment with the lat- 75

eral offset portions of the front edge 10 of the plate 72. The shoe thus positioned will have moved the block 176 rearward to a predetermined position. The screw 225 securing the plate 220 to the base portion 218 of the platform 214 is then loosened and the interlocking heel 28 to be attached to the shoe is positioned upon the plate with its breast in engagement with the abutments 216. The plate 220 is then moved rearward with relation to the base portion 218 of the platform 214, the rear end of the heel forcing the abutment 226 rearward until the stop 136 has been swung into forced relation with the face 190 of the block 176. The screw 225 is then tightened to secure the plate 220 and the base portion 218 of the platform 214 to each other.

Having described the invention, what I claim as new and desire to secure by Letters Patent of the United States is:

1. A heel-seat fitting machine having, in combination, means for reducing the heel-end portion of an attached sole of a shoe for the reception of an interlocking heel, a back gage for positioning the heel-seat portion of the shoe with relation to said means, a heel gage comprising relatively movable abutments constructed and arranged to engage the rear face of the heel and the bottom of a sole-receiving channel formed in the breast of the heel, respectively, and mechanism movable in response to the relative movement of said abutments for locating the back gage in a predetermined position in accordance with the relative positions of the abutments.

2. A heel-seat fitting machine having, in combination, a plate for supporting the heel-end portion of an attached sole of a shoe, a back gage for positioning the heel-seat portion of the shoe with the sole upon said plate, a knife for reducing said heel-end portion of the sole for the reception of an interlocking heel, a gage comprising a member for supporting the heel and stationary and movable abutments constructed and arranged to engage the breast and the rear end respectively of the heel mounted upon said member to measure the heel lengthwise, a spring for forcing a projecting lip of the heel measured by said abutments toward said member, and means connected to said movable abutment for locating the back gage in a predetermined position in accordance with the position of the movable abutment of the heel gage.

3. A heel-seat fitting machine having, in combination, means for reducing the heel-end portion of an attached sole of a shoe for the reception of an interlocking heel, a back gage for positioning the heel-seat portion of the shoe with relation to said means, a heel gage comprising stationary and movable abutments constructed and arranged to engage the rear end of the heel and the bottom of a sole-receiving channel formed in the breast of the heel, respectively, and mechanism movable in response to movement of said movable abutment of the heel gage for locating the back gage in a predetermined position in accordance with the position of said movable abutment.

4. A heel-seat fitting machine having, in combination, a plate, a knife for forming at the rear end of an attached sole of a shoe supported by the plate a tab which tapers rearwardly from the ends of the heel-breast line of the sole and is of suitable size to fit in a sole-receiving channel formed in the breast of an interlocking heel to be attached to the shoe, means for operating said knife, a back gage for positioning the

shoe and the heel-end portion of its sole with relation to said plate preparatory to reducing the heel-end portion of the sole to form said tab, a heel gage comprising stationary and movable abutments constructed and arranged to engage the breast and the rear faces, respectively, of the heel, and mechanism movable in response to movement of said movable gage for locating the back gage in a predetermined position in accordance with the position of said movable abutment.

5. A heel-seat fitting machine having, in combination, means for receiving either mechanism for supporting and reducing the heel-seat portion of an attached sole of a shoe for the reception of a Louis or Cuban heel, or mechanism for supporting and reducing the heel-end portion of an attached sole of a shoe for the reception of an interlocking heel, a back gage for positioning the heel-seat portion of the shoe being operated upon in the machine with relation to the sole-supporting and reducing mechanism of the machine, a heel gage comprising stationary and movable abutments for measuring the Louis or Cuban heel lengthwise, means for locating the back gage in a predetermined position in accordance with the position of the movable abutment of said heel gage, and a unit constructed and arranged to be readily secured in operative position upon and removed from said heel gage, said unit comprising a stationary abutment which cooperates with the movable abutment of said heel gage to measure the interlocking heel lengthwise.

6. A heel-seat fitting machine having, in combination, means for receiving either mechanism for supporting and reducing the heel-seat portion of an attached sole of a shoe for the reception of a Cuban or Louis heel, or mechanism for supporting and reducing the heel-end portion of an attached sole of a shoe for the reception of an interlocking heel, a back gage for positioning the heel-seat portion of the shoe being operated upon in the machine with relation to the sole-supporting and reducing mechanism of the machine, said back gage comprising an extension block which may be secured to the shoe-engaging portion of the back gage equipped for Louis or Cuban work in order to accommodate interlocking work, a heel gage comprising stationary and movable abutments for measuring the Louis or Cuban heel lengthwise, means for locating the back gage in a predetermined position in accordance with the position of the movable abutment of said heel gage, and a unit which may be readily secured in operative position upon said heel gage preparatory to operating upon interlocking work, said unit being constructed and arranged to support the interlocking heel and having one or more abutments constructed and arranged to cooperate with the movable abutment of said heel gage to measure the heel lengthwise.

7. A heel-seat fitting machine having, in combination, means for receiving either mechanism for supporting and reducing the heel-seat portion of an attached sole of a shoe for the reception of a Louis or Cuban heel, or mechanism for supporting and reducing the heel-end portion of an attached sole of a shoe for the reception of an interlocking heel, a back gage for positioning the heel-seat portion of the shoe being operated upon in the machine with relation to the sole-supporting and reducing mechanism of the machine, a heel gage comprising station-

ary and movable abutments for measuring the Louis or Cuban heel lengthwise, means for locating the back gage in a predetermined position in accordance with the position of said movable abutment of the heel gage, a platform which may be readily secured in operative position upon and removed from said heel gage, said platform having a face for supporting an interlocking heel and a shoulder extending above said face, and a finger carried by said movable abutment and movable upon the movable abutment to and from its operative position adjacent to said face of the platform, said finger when in its operative position being constructed and arranged to engage the bottom of a sole-receiving channel formed in the breast of the heel and to cooperate with said shoulder of the platform to measure the distance between the rear end of the heel and the bottom of said channel.

8. A heel-seat fitting machine having, in combination, means for receiving either mechanism for supporting and reducing the heel-seat portion of an attached sole of a shoe for the reception of a Louis or Cuban heel, or mechanism for supporting and reducing the heel-end portion of an attached sole of a shoe for the reception of an interlocking heel, a back gage movable rearwardly under pressure of the shoe being operated upon in the machine, a stop constructed and arranged to limit rearward movement of the back gage when the heel-seat portion of the shoe has been moved to a predetermined position with relation to the sole-supporting and reducing mechanism of the machine, a heel gage comprising stationary and movable abutments for measuring the Louis or Cuban heel lengthwise, connections between the movable abutment of the heel gage and the stop for locating said stop in a predetermined posi-

tion in accordance with the position of the movable abutment of the heel gage, means for initially adjusting said connections with reference to said movable abutment to locate the stop in correlated relation with the movable abutment, and a platform constructed and arranged to be readily secured in operative position upon and removed from the heel gage, said platform comprising one or more abutments which cooperate with the movable abutment of the heel gage to measure the interlocking heel lengthwise.

9. A heel-seat fitting machine having, in combination, means for receiving either mechanism for supporting and reducing the heel-seat portion of an attached sole of a shoe for the reception of a Louis or a Cuban heel, or mechanism for supporting and reducing the heel-end portion of the attached sole of a shoe for the reception of an interlocking heel, a back gage for positioning the heel-seat portion of the shoe being operated upon in the machine with relation to the sole-supporting and reducing mechanism of the machine, a heel gage comprising stationary and movable abutments for measuring the Louis or Cuban heel lengthwise, means for locating the back gage in a predetermined position in accordance with the position of the movable abutment of said heel gage, and a platform having a base portion which is constructed and arranged to be secured in a predetermined operative position upon the heel gage, said platform comprising a heel-supporting plate which is movable into different adjusted positions with relation to said base portion and has an abutment constructed and arranged to cooperate with the movable abutment of the heel gage to measure the interlocking heel lengthwise.
